UNITED STATES PATENT OFFICE

162,842

DRIP CAP

Robert L. Klein, Rochelle Park, N. J.

Application September 1, 1950, Serial No. 12,014

Term of patent 14 years

(Cl. D54—2)

To all whom it may concern:

Be it known that I, Robert L. Klein, a citizen of the United States, residing at Rochelle Park, in the county of Bergen and State of New Jersey, have invented a new, original, and ornamental Design for a Drip Cap, of which the following is a specification, reference being had to the accompanying drawing, forming part thereof.

The figure is a perspective view of a drip cap, showing my new design.

I claim:

The ornamental design for a drip cap, as shown.

ROBERT L. KLEIN.
